CLAIM

The ornamental design for a beverage filter, as shown and
described.

DESCRIPTION

FIG. 1 is a top perspective view of a beverage filter showing
my new design.

FIG. 2 is a bottom perspective view thereof.

FIG. 3 is a left side elevational view thereof.

FIG. 4 is a front elevational view thereof.

FIG. 5 is a right side elevational view thereof.

FIG. 6 is a rear elevational view thereof.

FIG. 7 is a top plan view thereof; and,

FIG. 8 is a bottom plan view thereof.

The broken lines depict portions of the beverage filter that
form no part of the claimed design.

1 Claim, 8 Drawing Sheets
